[57] CLAIM

The ornamental design for a container cover with hinge pin, as shown and described.

DESCRIPTION

FIG. 1 is a top plan view of a container cover with hinge pin embodying my new design;

FIG. 2 is a side elevational view thereof, the other side being a mirror image thereof;

FIG. 3 is a front elevational view thereof;

FIG. 4 is a rear elevational view thereof;

FIG. 5 is a bottom plan view thereof;

FIG. 6 is a bottom plan view of a second embodiment of the container cover with hinge pin, the top view being identical to the first embodiment of FIG. 1;

FIG. 7 is a bottom perspective view of FIG. 1; and,

FIG. 8 is a bottom perspective view of FIG. 6.

FIG. 1

FIG. 2

FIG. 3

FIG. 4

FIG. 5

FIG. 6

FIG. 7

FIG. 8
